CLAIM

The ornamental design for a handbag, as shown and described.

DESCRIPTION

FIG. 1 is a front perspective view of a handbag showing my new design;

FIG. 2 is a front view thereof;

FIG. 3 is a rear view thereof;

FIG. 4 is a right side view thereof, with the left side being a mirror image;

FIG. 5 is a top view thereof; and,

FIG. 6 is a bottom view.

The broken line showing of the handles, closure flap, portion of the handbag, buttons, and buckles is for illustrative purposes only and forms no part of the claimed design.
